UNITED STATES PATENT OFFICE.

JOSEPH LIMONCELLO, OF CHICAGO, ILLINOIS.

KNOCKDOWN CRATE.

1,225,665.

Specification of Letters Patent.

Patented May 8, 1917.

Application filed August 17, 1916. Serial No. 115,365.

To all whom it may concern:

Be it known that I, JOSEPH LIMONCELLO, a subject of the King of Italy, residing at Chicago, in the county of Cook and State of Illinois, have invented certain new and useful Improvements in Knockdown Crates, of which the following is a specification.

My invention relates to improvements in knock-down crates, open drums or barrels, and has particular reference to containers of this character especially adaptable for shipping bananas, other fruits, vegetables and the like.

The object of my invention is to provide a crate which can be made at low cost of construction; which can be packed in knock-down condition, thus occupying a minimum of space for storage or for shipping; which can be readily and quickly set up for use by unskilled labor, and which may, after being used, again be knocked-down for re-shipment to be again used.

My invention concerns more specifically the means employed for interlocking the terminal ends of the top and bottom hoops; the means afforded for securing the heads in place in knock-down and set-up condition, and other features of construction more minutely hereinafter pointed out.

30 In the drawings:

Figure 1 is a side elevation of a crate set up and ready to receive the contents to be shipped therein;

Fig. 2 is an enlarged plan view of the crate, with the heads removed;

Fig. 3 is a plan view of the crate knocked-down ready to be stacked with others of like character, in relatively small dimensions for re-shipment or for storage.

40 Fig. 4 is a section taken through one vertical wall and the upper head of Fig. 1.

Fig. 5 is a similar view of the bottom end.

Fig. 6 is a fragmentary plan showing the manner of attaching the inner lining of the 45 crate, when a lining is to be used.

Fig. 7 is a section taken on line 7—7 of Fig. 6.

In all of the views the same reference characters are employed to indicate similar 50 parts.

The structure which I am herein seeking

to patent is an open drum or grate, adaptable for shipping bananas or other fruits or vegetables. The vertical walls of the container are made of a series of spaced-apart slats or staves 10, preferably of thin inexpensive wood, or other suitable material, being held together at their respective ends by thin flexible wooden hoops 11—11' positioned outside the staves at their upper and lower ends respectively. Inside the staves and opposite the wooden hoops I have provided wire reinforcing hoops or rings 12—12'. Staples 13 are driven over the wire hoops through the slats 10 into the flat 65 hoops and clenched on the outer side as at 14, as more clearly shown in Fig. 7. The wire hoop 12, at the upper end of the structure is located a slight distance below the upper edges of the slats 10, substantially 70 equal to the thickness of head 15, so that when the head is placed in position in the walls formed by the slats it will rest upon the wire hoop 12. To reinforce the upper wire 12 I nail small wooden cleats 16 to 75 selected slats immediately under the wire, so that downward pressure upon the head 15 is carried by both the wire fasteners and the cleats. As the lower head 15' of the structure rests above the wire at its lower end, 80 cleats 16' are placed below the wire hoop 12' on certain selected slats for the purpose of reinforcing or strengthening the head holding means.

When a lining, such as is indicated at 18, 85 is employed, the upper and lower ends are secured by placing the same between the staves and wire hoops, the staples 13 passing through the lining and fastening it in place. The lining 18 may be composed of tough 90 fibrous material, such as paper or the like, and is placed in position and held as above described at the time when the structure is being made or the parts fastened together and therefore becomes an inseparable part 95 of the structure.

Wires 19 and 20 are placed across the series of slats 10, at uniform distances between the hoops 11 and 11' and are secured thereto by staples 21 and 21'. The wire hoops 12 100 and 12' are each bent at their ends into hooks 12^a and 12^b, so that when the barrel

or crate is formed into a cylinder, shown in Fig. 2, the hooks 12^a and 12^b are caused to engage to hold the structure in cylindrical shape. The ends 12^a and 12^b of the wires 12 and 12' are passed through openings 23 and 23', made through the hoops between the adjacent slats near the ends where the structure is held together by the hooks 12^a and 12^b. After passing through the holes or openings 10 23 and 23', they are secured on the outside of the structure, by staples 24, 24'. The terminal slats are within the terminal ends 12^a, 12^b of the wire hoops.

The heads 15 and 15' are secured in position by cross wires 25 and 26, 25' and 26' respectively. These wires are secured thereto by means of staples 27 that pass through the heads. The wires on the upper and lower heads are provided with ends 28, 20 28', respectively that extend beyond the heads to form fasteners. Three staples 29, 30 and 31 and a similar set of three staples of which only 29' and 31' are visible in the drawing are driven part-way through the hoops 11, and 11' respectively and through the staves or slats 10 and serve as means for holding the ends 28, 28' of the cross wires when the heads 15 and 15' are in place. In packing the structure for shipment, as shown in Fig. 3, the head 15 is placed thereon in the position shown with the head 15' placed therebelow. The wire ends 28, 28' of each of the heads, pass through oppositely positioned staples on the 30 outside of each end of the structure respectively and are secured thereto by being bent into eyes or loops.

To set up the structure ready for use it is only necessary to bend the slats with the 40 attached hoops, into cylindrical form until the hooks 12^a and 12^b on the ends of the wire hoops 12-12' engage, as shown in Figs. 1 and 2. It will be observed that the ends 11^a of the flat hoops 11 and 11', over-lap the ends 11^b, as more clearly shown in Fig. 2 for the purpose of reinforcing the structure at the juncture. After the heads are placed in position, resting on the hoops 12-12' the wire ends 28-28' registering 50 with the outer staples are bent over the edges of the crate and pass through the staples and then bent outwardly as indicated in Figs. 4 and 5 to lock the heads in position. The remaining wire ends are bent 55 over the edges of the crate and fastened to the wire hoops adjacent the points where their ends are hooped together.

The wire hoops 19 and 20 are each provided on one end with eyes 19' and 20' respectively. The free ends of the wires 19 and 20 are passed through these eyes and bent back, as shown in Fig. 1, thereby providing hoops for strengthening the central portion of the structure.

In the particular embodiment illustrated, 65 I have shown the crate, or barrel provided with a larger upper end which is the usual form of a banana crate, but it is evident that the structure may be made of uniform diameter as in open drums or barrels for the 70 shipment of fruit or vegetables and it is further manifest that a lining 18 may be employed when required and secured and placed in the structure in the manner heretofore described. 75

Having now described my invention, what I claim and desire to secure by Letters Patent is:—

1. A knock-down structure of the character described comprising a series of spaced-apart slats or staves; flat hoops crossing the outside surfaces of said slats near their respective ends; wire hoops, secured to the inside surfaces of said slats within the diametric plane in which said flat hoops are 85 located; fastening devices passing over the wire hoops through the slats and through the flat hoops and clenched on the outside thereof; heads resting on the inner wire hoops; hooks on the ends of the wire hoops 90 to hold the structure in cylindrical shape.

2. A knock down structure of the character described comprising a series of spaced-apart slats or staves; flat hoops crossing the outside surfaces of said slats near their respective ends; wire hoops, secured to the inside surfaces of said slats within the diametric plane in which said flat hoops are located, when the structure is assembled; fastening devices passing over said wire 95 hoops through the slats and through the flat hoops, clenched on the outside thereof and heads resting on the inner wire hoops; hooks on the ends of the wire hoops to hold the structure in cylindrical shape and crossing 100 wires for fastening the heads in place, crossing the outside surfaces of the heads, having their ends secured in staples driven into the outside of the assembled structure.

3. In a structure of the character described the combination of a series of spaced-apart slats or staves; flat flexible hoops extending around the outside near the ends thereof and lapped at their meeting ends; a wire hoop at each end, inside the structure 115 when set up, each hoop having hooks at each of its ends, located on the outside of the structure, overlying the over lapped ends of the flat hoops when the structure is set up for separable engagement and cleats secured 120 to selected slats below said wire hoops to support the heads to be inclosed therein, and a head overlying each wire hoop.

4. In a structure of the character described the combination of a series of 125 spaced-apart slats or staves; flat flexible hoops extending around the assembled slats near their ends, connected thereto and hav-

ing over-lapped ends and wire hoops on the inside of the structure under said flat hoops, the ends whereof are provided with separable hooks located outside of said structure, said wire hoops extending through the structure so as to include a plurality of slats between the outwardly projecting ends.

In testimony whereof I hereunto set my hand in the presence of two subscribing witnesses.

JOSEPH LIMONCELLO.
